UNITED STATES PATENT OFFICE

117,575

DESIGN FOR A CAMERA

John B. Nelson, Rochester, N. Y., assignor to Eastman Kodak Company, Rochester, N. Y., a corporation of New Jersey

Application February 23, 1939, Serial No. 83,169

Term of patent 3½ years

To all whom it may concern:

Be it known that I, John B. Nelson, a citizen of the United States and residing at Rochester, in the county of Monroe and State of New York, have invented a new, original, and ornamental Design for a Camera, of which the following is a specification, reference being had to the accompanying drawing, forming part thereof and in which:

Fig. 1 is a front view; and
Fig. 2 is a plan view of a camera showing my new design.

The essential feature of my design resides in the decorative panel shown in full lines.

I claim:

The ornamental design for a camera, as shown and described.

JOHN B. NELSON.
